Application April 14, 1943, Serial No. 482,971

7 Claims. (Cl. 60—53)

This invention relates to motion reproducing or follow-up mechanism in which the movement of one member, herein referred to as the primary element, is to be reproduced by another member, herein termed the secondary or follower element.

More particularly this invention has to do with such mechanism in which the primary element does not have sufficient power to drive the secondary element, but instead governs a control for a supplemental power device called a servo motor.

In such systems a differential means compares the incoming movement which is to be reproduced and the response or output of the servo motor. In other words it compares the movements of the primary and secondary elements and its output is representative of the error, that is, of the lack of positional agreement between the two elements.

A simple form of such a follow-up mechanism is one in which the power device is a variable speed motor or drive and the error, represented by the output of the differential, is utilized directly to control the speed so as to obtain the desired reproduction of motion. Customarily the differential output controls a speed regulating device for the motor or drive through a fixed ratio connection so that the speed of the response and hence of the elimination of the error is a direct function of the error. Conversely, when the secondary element is being driven at the same speed as the primary element there is an inherent positional error proportional to the speed.

It is recognized that such controls are not ideal in effecting synchronization when there is a substantial error to be erased. According to the characteristics of the system they either result in too rapid acceleration of the response when the error is large or they are sluggish and require an undue time to synchronize.

The object of this invention is to provide a control in such systems which will effect synchronization in a minimum of time and at a predetermined acceleration which will be best suited to the characteristics of the system. Specifically it is an object to make the acceleration substantially uniform while synchronizing and of a value suited to the power device and load conditions and which will bring the members into synchronization promptly and at the maximum speed consistent with the synchronizing conditions.

According to the invention the improvement in synchronizing is obtained by making the speed of the response or in certain forms, the rate of removal of the error proportional to the square root of the error. This is according to the law of uniformly accelerated motion, wherein the instant velocity is proportional to the square root of the

distance moved. To apply this to the problem under consideration, if the speed of the response or the speed at which the error is being removed be represented by V , and the error or distance from synchronous relation of the elements be D , and the predetermined or chosen acceleration be denoted by a , then the equation which it is desired to apply in the control mechanism is $V = \sqrt{2aD}$.

To maintain this condition the ratio between 10 the error D and the rate of the response or the rate of removal of the error V must constantly change as synchronization is approached. By the invention this change in ratio is accomplished by a cam mechanism introduced in the mechanical connection between the output of the differential means and the control member of the speed regulating device. The cam surface is so formed that the control member is positioned to provide a velocity of output of the speed regulating device 15 which is proportional to the square root of the error D . The acceleration is chosen according to the characteristics of the particular system.

The invention will now be explained in connection with the diagrams and apparatus illustrated 20 in the accompanying drawings and will be thereafter pointed out in claims.

Fig. 1 is a schematic representation of an apparatus embodying the invention;

Fig. 2 is a graph showing curves representing 25 the ratio between the error, D , and the rate of removal of the error, V , both when the rate of removal is proportional to the square root of the error, according to the present invention and, by way of comparison, when the rate of removal, V , 30 is proportional to the error, D , as in prior systems;

Fig. 3 is a graph showing curves representing 35 the progressive values of the error, D , during the synchronizing period for the two conditions depicted in the graph of Fig. 2, and also a curve representing the progressive values of the rate V under the depicted condition when, as contemplated by the invention, the rate of removal of the error or the speed of the response is proportional 40 to the square root of the error;

Fig. 4 is a schematic representation of an embodiment of the invention in which the speed regulating member of the variable speed power device is positioned by an hydraulically operated 45 relay mechanism;

Fig. 5 is a view similar to Fig. 4 but showing a 50 modification of the hydraulically operated mechanism; and

Fig. 6 is a similar view showing a still further 55 modification of the hydraulically operated mechanism.

The principle will be explained first by reference to the form of mechanism represented in the diagram of Fig. 1. The shaft 1 represents the primary element and the shaft 2 represents the secondary element. The differential 3 is connected between these and the output of the differential drives shaft 4. The constant-speed power motor 5 operates the shaft 2 through a variable speed drive 6 the rate element or control member of which is a ball carriage 7 the position of which is determined by the differential output shaft 4.

Heretofore the positioning of the speed element has been in direct proportion to the error, that is, $V=kD$ in which k is a selected conversion constant. In other words there has been a fixed drive ratio between the members corresponding to the shaft 4 and ball carriage 7, such as would be the case, for example, if the arm 8 of the ball carriage were provided with a rack coacting with a pinion on the shaft 4. Such a drive gives accelerations and speeds varying with the error when synchronizing, and introduces an error proportional to the speed while following.

According to the invention the ratio of movement between the members corresponding to the shaft 4 and the ball carriage or speed regulating member 7 is a variable such that, when synchronizing, the acceleration of the output of the variable speed drive is a predetermined constant. As shown this is effected through a cam and cam follower introduced in the drive, the cam surface being shaped to correspond to the curve representing the ratio $V=\sqrt{2aD}$. As shown in Fig. 1 this cam surface is a groove 9 on the cylindrical cam 10, and a pin 11 on the arm 8 serves as a cam follower. The positioning of the speed element will therefore be such as to effect the ratio represented by the stated equation.

This ratio for a given value of acceleration is shown in Fig. 2. There by way of illustration a value of eight is selected for the acceleration. That makes the value of V , which may be taken as the position of the ball carriage 7, or the velocity of the response as represented by the rate of movement of the shaft 2 or the rate of erasure of the error as represented by the movement of shaft 4, all three of which are proportional, equal to four times the square root of the position of the shaft 4, that is, $V=\sqrt{2 \cdot 8 \cdot D}$ or $V=4\sqrt{D}$. This assumes for the sake of simplicity, that the shaft 1 is stationary for the time being, or, in other words, that the shaft 1 has introduced a certain primary movement which moved the ball carriage off center a certain amount, and that the motor 5 through the variable speed drive is moving the shaft 2 a corresponding amount. At the end of this response movement the shaft 2 will be in agreement with the movement introduced by shaft 1 and the ball carriage will be back at the center position. The principle is the same, of course, if shaft 1 continues to move and shaft 2 accelerates to come into speed synchronism with it. The ball carriage 7 in such case will take a position off center sufficient to cause shaft 2 to move at the same rate as shaft 1 but with a lag sufficient to displace the ball carriage the proper amount. The amount of this lag or velocity error is expressed by the equation

$$D = \frac{V^2}{2a}$$

or

$$D = \frac{V^2}{16}$$

for the assumed acceleration.

The curve of Fig. 2 which satisfies the equation $V=4\sqrt{D}$ is numbered 9 for the reason that it determines the shape of cam groove 9 for this selected value of a , it being understood that the curve of Fig. 2 represents only one-half of the cam groove, the other half being the reverse curve. When the error becomes small the slope of the curve following the equation $V=\sqrt{2aD}$ approaches so near the vertical that a cam made strictly in accordance therewith would be inoperative, for this reason the groove 9 on the cam 10 is made of uniform lead near the center or zero position so that the operation over this portion of the cam is in accordance with the equation $V=kD$.

Assuming twenty-five to be the maximum value of error D and twenty to be the maximum value of velocity V , a constant ratio between V and D as previously used would be represented by the curve 9a of Fig. 2, in this case of course a straight line. The ratio or constant k in this case is eight tenths, that is, $V=kD$ or $V=.8D$.

By the use in connection with the invention of the selected acceleration of eight (say 8° per second per second), the value of V will decrease from 20° per second to zero in $2\frac{1}{2}$ seconds. This is shown by the curve 12 of Fig. 3, which is in accordance with the equation $V=(2\frac{1}{2}-t)a$ or $V=20-8t$.

The value of D during the synchronization when a cam groove corresponding to the curve 9 is used is shown by the curve 13, which is in accordance with the equation $D=25-20t+4t^2$. The curve 14 represents the value of D during synchronization when the ratio between V and D is kept constant. It will be seen that in such case, as when a gear drive is used, the error approaches zero at a much slower rate and theoretically never actually reaches zero. The error resulting from this condition is minimized when the cam is used because of the relatively large effect of a small change of error near synchronization, because the constant k of the equation $V=kD$, which is effective over the portion of the cam near zero error, can be made relatively large.

As has previously been explained the error of the follow-up shown in Fig. 1 when following a moving signal or primary element is substantially proportional to the square of the velocity. In many instances this error is objectionable, however, it may be overcome by utilizing forms of control in which the error is a function of the acceleration or change of acceleration. In the embodiment of the invention shown in Figs. 4, 5 and 6 the error when following a moving signal is a function of the changes in velocity but when the response is synchronizing with the incoming signal the velocity of removing the error is substantially proportional to the square root of the error, that is, $V=\sqrt{2aD}$. A suitable type of control in which the normal error when following the incoming signal is a function of the rate of change of acceleration is shown in the hydraulic control of Figs. 4, 5 and 6. In this respect the control follows the construction disclosed in the copending application of William H. Newell, Serial No. 313,678 and assigned to the same assignee.

The construction of Fig. 4 is a simple construction in which the cam 10 operates the main valve of the hydraulic control directly instead of through a pilot valve. This assumes sufficient power in the incoming movement to do this work.

A handle is shown in Fig. 4 as representative of any source of primary movement applied to the shaft 1 constituting the primary element, and a

secondary element, as in Fig. 1 consists of a shaft 2, a differential 3 being connected between the two shafts and driving the cam 10 through the output shaft 4. Dials are shown to indicate the positions of the primary and secondary elements.

The variable speed drive 6 in this case is an hydraulic speed gear of well known form which includes an hydraulic pump known as the "A" end and an hydraulic motor known as the "B" end which is connected to the response shaft 2. 10 The pump is rotated at constant speed by the motor 5 and the speed of the motor or "B" end is determined by the position of a tilting box or swash plate in the "A" end actuated by a crank arm 15.

The crank arm 15 is positioned by a reciprocating hydraulic piston 16 slidable in a cylinder 17 having ports at its opposite ends connected to high and low pressure hydraulic fluid through valve means to be described. The left end of the piston 16 has a reduced extension slidable in a reduced axial extension of the cylinder 17, so that the active area of the left end of the piston is, say, one-half that of the right end. The pressures will therefore be balanced when that on the right end is one-half that on the left end. A high pressure conduit 18 leads into the cylinder 17 on the left end of the piston, and a low pressure conduit 19 leads into the cylinder on the right end of the piston. These conduits lead from a valve 30 block 20 provided with passages and valves.

The passages referred to are the high pressure passage 21 connected to the pressure side of a pump (not shown), and an exhaust passage 22 connected to the exhaust pressure or intake side 35 of the pump through a suitable supply reservoir. The high pressure conduit 18 of cylinder 17 communicates with the high pressure passage 21, and that passage also has two spaced branches 21a leading to a valve bore 23 in the block 20. The 40 exhaust passage 22 has two spaced branches 22a leading to the bore 23, the two exhaust branches being outside the two pressure branches.

Two piston valves 24 and 25 slide in the bore 23, their mid portions being reduced and their length being such as to just lap the ports of the pressure and exhaust branches on their respective sections of the bore when the valves are in their central positions. The bore is closed at its ends and the conduit 19 leads to the left end adjacent the main valve 24 so that the conduit and the connected ends of the cylinder 17 and bore 23 constitute a closed chamber that contains hydraulic fluid. A branch 19a leads into the bore 23 opposite the regulator valve 25 midway between the pressure and exhaust ports controlled thereby.

The valve 25 on its outer end has a reduced extension that slides in a correspondingly reduced extension of the bore 23, thereby making the active area on that end one-half that on the inner end. The pressure passage 21 has a branch 21b leading to the end of the bore 23 at the reduced end of the valve 25.

A conduit 26 that includes passages in the valve block and an outside pipe connecting the passages, 65 connects the bore 23 at a point opposite the valve 24 midway between the pressure and exhaust ports lapped thereby to the space in the bore between the valves 24 and 25.

The arm 8 in this case is a pivoted lever fulcrumed at its lower end and extending transversely of the axis of the cam 10, so that it is rocked on its pivot as the follower 11 rides in the cam groove 9. A horizontal link 27 has a slotted pivotal connection with the lever 8 between its 70

ends so as to be reciprocated thereby, and the link 27 has one end pivotally attached to a rod 28 axially fixed to the valve 24 and slidable through a bearing in the block 20. Thus rocking movement of the lever 8 is transmitted directly to produce longitudinal movement of the valve 24.

Assume the parts in zero position, as shown in Fig. 4, and movement of the handle on the shaft 1 in a clockwise direction as viewed from the left. The shaft 4 will turn in a counter-clockwise direction. This will turn the cam 10 in the same direction and cause the upper end of the lever 8 to move to the right. This will move the valve

15 24 to the right and reduce the pressure on the fluid in conduit 19 and the chamber at the right end on piston 16. The high pressure from conduit 18 acting on the left end of piston 16 causes a movement of piston 16 to the right to restore a balance of pressures on the piston, and hence a movement of crank 15 and the tilting box of the "A" end of the variable speed gear. The "B" end is thus caused to rotate at a speed proportional to the displacement of the tilting box, which movement is transmitted as a response through shaft 2 to the differential 3 to neutralize the input movement of shaft 1. Eventually the follower 11 is again centralized thereby, and the valve 24 is brought back to its original position and the state of equilibrium represented in Fig. 4 is again restored.

The above explanation neglects the compensations or corrections for the speed and acceleration errors and therefore the operation is the same as explained for Fig. 1. The conduit 26 and the space between the valves 24 and 25 contains hydraulic fluid. The movement of the main valve 24 to the right imparts similar motion to the regulator valve 25 through the intervening hydraulic fluid. At the same time the valve 24 uncovers the port of the adjacent pressure passage 21a and admits pressure fluid to the conduit 26 at a rate representing a function of the displacement of valve 24 from its central position. 45 A restriction in the conduit 26 and the shape of the intermediate reduced portion of valve 24 are designed to effect the desired function. The displacement of the piston 25 is therefore proportional to the square root of the error, that is, the movement of valve 24, plus the amount of pressure fluid admitted through the conduit 26 due to the displacement of valve 24.

This displacement of valve 25 uncovers the exhaust port an amount proportional to the sum 55 of the two quantities, namely the square root of the error, represented by movement of valve 24, and the flow through conduit 26 due to the displacement of valve 24, and to that extent branch 19a is connected to exhaust. The conduit 19a has a restriction to modify the flow of fluid from the conduit 19 to exhaust. The flow of hydraulic fluid from the conduit 19 to exhaust reduces the volume of hydraulic fluid contained in the normally closed chamber so that as the valve 24 is brought back to its original position due to the movement of the shaft 2 the crank 15 of the "A" end of the variable speed gear remains displaced at an angle which causes the "B" end to continue to drive the shaft 2 at a speed corresponding to the rate of rotation of shaft 1 but without the speed error or the lack of complete synchronism found with the construction of Fig. 1. Although valve 24 is now back at its central position the valve 25 is still displaced due to the previous flow through conduit 26 and therefore fluid continues

to flow from conduit 19 through conduit 19a so that the control arm of the "A" end of the variable speed gear is displaced still further and shaft 2 not only overtakes but slightly passes shaft 1. This causes valve 24 to move to the left of its central position and the increased pressure to the left of valve 24 causes the piston 16 to move to the left to slow down shaft 2 because the rate of reduction of the volume of the chamber to the left of valve 24 exceeds the outward flow of fluid through the conduit 19a. The movement of valve 24 to the left likewise moves the valve 25 to the left until it reaches its central position and the flow through conduit 19a ceases. While the valve 24 is to the left of its central position 15 the exhaust port 22a is connected to the conduit 26 so that fluid flows from the space between the valves 24 and 25. As the main valve 24 then returns to its central position the shaft 2 slows down slightly and the valve 25 remains substantially in its central position because the constants of the system are so selected that the rate of flow through conduit 26 from the space between valves 24 and 25 neutralizes the effect on the valve 25 of the movement of valve 24 toward its central position. When the valve 24 has thus returned to its central position the valve 25 is also at its normal central position and the low pressure hydraulic system of conduit 19 is again stabilized as shown in Fig. 4 except that the crank 15 is displaced an appropriate amount.

During normal following operation of the apparatus of Fig. 4 the follower 11 remains substantially at the center of the groove 9 of cam 10. If for any reason the error exceeds that due to normal following of the movements of the primary element the apparatus then acts to remove the error at a rate in accordance with the equation $V = \sqrt{2aD}$ or $V = 4\sqrt{D}$ for the selected value of eight for the constant acceleration or deceleration of synchronizing. Assuming that the error is sufficient to cause the follower 11 to be at the extreme right-hand end of the cam 10, then the main valve 24 will be at the extreme right-hand end of its travel and the piston 16 will be at the right-hand end of its travel so that the crank arm 15 and the tilting box of the "A" end are set for maximum speed of the response shaft 2 in the direction to remove the error. As the shaft 2 now turns, the follower 11 follows the cam groove 9 toward the center of the cam, the main valve 24 moves toward its center position thus forcing fluid through conduit 19 to return the piston 16 and crank arm 15 to their central position. It will be seen that as the follower 11 approaches the center of the cam 10 where the slope is greater, then the rate of rotation of the shaft 2 and the cam 10 becomes slower and slower with the combined effect that the movement of the valve 24 and crank arm 15 are substantially uniform, that is, the rate of change of the velocity of the output of the "B" end or the acceleration is a constant. During the operation of synchronizing the effect of the movement of valve 24 on the movement of the crank arm 15 so predominates over the effect of the flow through passage 19a that this flow has very little effect on the overall operation and for practical consideration may be neglected.

The control mechanism of Fig. 5 differs from that of Fig. 4 principally in that it employs a pilot valve and thus relieves the primary moving part of the load of adjusting the main control valve.

Instead of being pivoted at its lower end to a fixed fulcrum, the lever 8 is pivoted at its lower end to the stem 28 of a pilot valve 30. This pilot valve through a passage 30a controls the pressure at the right end of valve 25a which in this case, unlike the corresponding valve 25, has its two ends of equal active area.

The pilot valve 30 slides in a bore 31 and controls ports of pressure passage 21 and of an exhaust passage 32. An exhaust passage 33 also communicates with the space behind the pilot valve and with the exhaust port lapped by valve 25a.

The piston 16a, unlike piston 16, has both ends of equal active area, and the left end, instead of being opposed by full pressure fluid is opposed by a reduced pressure controlled by reducing valve 34. This valve has full pressure on one end which is of reduced area and its other end, which communicates with the left end of cylinder space 17, is alternately connected with pressure from passage 21 and exhaust in passage 33 through ports controlled by the valve 34, thus maintaining a constant reduced pressure on the left end of piston 16a. When the pressure in conduit 19 on the right end of piston 16a equals that on the left end, the piston is in equilibrium.

As before, let us assume an incoming primary movement in a clockwise direction. The cam 10 is turned counterclockwise and the upper end of lever 8 is moved to the right. The lever is now fulcrumed at the center pivot and its lower end therefore moves to the left pulling pilot valve 30 to the left. This opens the passage 30a to exhaust and valve 25a moves to the right under the influence of the pressure in conduit 19 acting through the valve 24 and the hydraulic fluid between the valves 24 and 25a. The valve 24 thus moves to the right and through the rod 28 and link 27 moves the lever 8 to the right about the follower 11 as a fulcrum until the pilot valve 30 is returned to its central position. Simultaneously with the movement of valve 24 to the right the piston 16a and the crank arm 15 move to the right under the effect of the pressure on the left end of piston 16a. As with the construction of Fig. 4 the movement of fluid through passage 26 due to the displacement of valve 24 changes the volume of fluid between valves 24 and 25a and the displacement of valve 25a permits flow of fluid through passage 19a to vary the volume of fluid in the normally closed chamber including the conduit 19.

As explained in connection with Fig. 4 the follower 11 during normal operation remains substantially at the center of the cam 10 and the flow of fluid through passage 19a varies the volume of fluid in the closed chamber so that the piston 16a and the crank arm 15 take the proper position to cause the shaft 2 to be rotated at a rate corresponding to the rate of the shaft 1. When synchronizing from a large error the piston 16a is moved at a uniform rate the same as explained regarding Fig. 4 except that the return movement of valve 24 is controlled by the cam 10 acting through the pilot valve 30 instead of directly through the link 27 and the rod 28.

The construction of Fig. 6 adds a relay valve to the construction of Fig. 5, thereby making more power available to operate the tilting box, but the principle and general effect are the same.

A piston 16b corresponding to the piston 16a is in this case operated by full pressure, the control of the admission of pressure on one side

and the connection of the other side to exhaust, and vice versa, being under a relay valve 36.

The relay valve 36 is slideable in bore 37 in the valve block 20, and the conduit 19 leads to one end of the bore 37 while the other end of the bore connects with a source of reduced pressure under the control of the pressure regulating valve 38. This valve, like valve 34, has one end of reduced area opposed by full pressure from passage 21, and the valve controls the connection of the 10 space at the opposite end with either full pressure from passage 21 or exhaust through passage 39. This reduced pressure on the end of valve 38 is balanced by the full pressure on the reduced area of the other end. The valve 31 has three reduced portions separating four piston valve portions, the center reduced portion communicating with full pressure from passage 21, and the two outside reduced portions communicating with exhaust passage 40. Thus axial movement of the relay valve 36 connects the ports of the passages leading to the opposite end of piston 16b either with pressure or exhaust.

As with the previous construction, a clockwise incoming movement moves the upper end of lever 8 to the right and pulls the pilot valve 30 to the left thereby causing the main valve 24 to move to the right and the relay valve 36 to move to the left under the influence of the pressure acting on the right-hand end of valve 36. This movement of valve 36 connects the left end of piston 16b with pressure and the right end to exhaust, thereby tilting the speed regulator to the right and turning shaft 2 in the direction to subtract from the movement introduced into the differential by shaft 4. The effect of the cam 10 during normal following and synchronizing is the same as for the construction of Fig. 5.

Other embodiments of the invention will readily occur to those skilled in the art and it is not the intent that the invention shall be limited to the constructions used for illustration but only as required by the following claims.

I claim:

1. A motion reproducing mechanism including a primary element and a secondary element and means to cause the secondary element to reproduce the motion of the primary element comprising a power device for driving the secondary element, a speed regulating member for the power device, means for comparing the motion of the primary and secondary elements, and control means for the speed regulating member including a cam actuated by the output of the comparing means and a cam follower operatively connected to the speed regulating member.

2. A motion reproducing mechanism including a primary element and a secondary element and means to cause the secondary element to reproduce the motion of the primary element comprising a power device for driving the secondary element, a speed regulating member for the power device, means for comparing the motion of the primary and secondary elements, and control means for the speed regulating member including a cam actuated by the output of the comparing means and having a cam surface representing the ratio between the positional output of the comparing means and the speed of the power device when the latter is proportional to the square root of the former, and a cam follower operatively connected to the speed regulating member.

3. A motion reproducing mechanism including a primary element and a secondary element and

means to cause the secondary element to reproduce the motion of the primary element comprising a power device for driving the secondary element, a speed regulating member for the power device, means for comparing the motion of the primary and secondary elements, and control means for the speed regulating member including a cam actuated by the output of the comparing means and having a cam surface representing the ratio $V = \sqrt{2aD}$, and a cam follower operatively connected to the speed regulating member.

4. A motion reproducing mechanism including a primary element and a secondary element and means to cause the secondary element to reproduce the motion of the primary element comprising a variable speed power device for driving the secondary element, a speed regulating member for the power device, a differential connected between the primary and secondary elements, a hydraulically operated piston connected to operate the speed regulating member, a valve block having passages communicating with opposite ends of the piston and connected respectively with high and low hydraulic pressure, a slide valve in the block in control of the passages, an actuating link for the valve, and means operatively connecting the output of the differential with the link including means automatically operable to vary the ratio of movement of the output and of the link.

5. A motion reproducing mechanism including a primary element and a secondary element and means to cause the secondary element to reproduce the motion of the primary element comprising a variable speed power device for driving the secondary element, a speed regulating member for the power device, a differential connected between the primary and secondary elements, a hydraulically operated piston connected to operate the speed regulating member, a valve block having passages communicating with opposite ends of the piston and connected respectively with high and low hydraulic pressure, a slide valve in the block in control of the passages, an actuating link for the valve, and means operatively connecting the output of the differential with the link including a cam operated by the output and a cam follower on the link.

6. A motion reproducing mechanism including a primary element and a secondary element and means to cause the secondary element to reproduce the motion of the primary element comprising a variable speed power device for driving the secondary element, a speed regulating member for the power device, a differential connected between the primary and secondary elements, a hydraulically operated piston connected to operate the speed regulating member, a valve block having passages communicating with opposite ends of the piston and connected respectively with high and low hydraulic pressure, a slide valve in the block in control of the passages, an actuating link for the valve, and means operatively connecting the output of the differential with the link including a cam operated by the output and having a cam surface representing the ratio between the positional output of the differential and the rate of movement of the secondary element when the latter is proportional to the square root of the former, and a cam follower on the link.

7. A motion reproducing mechanism including a primary element and a secondary element and means to cause the secondary element to repro-

duce the motion of the primary element comprising a variable speed power device for driving the secondary element, a speed regulating member for the power device, a differential connected between the primary and secondary elements, a hydraulically operated piston connected to operate the speed regulating member, a valve block having passages communicating with opposite ends of the piston and connected respectively

with high and low hydraulic pressure, a slide valve in the block in control of the passages, an actuating link for the valve, and means operatively connecting the output of the differential with the link including a cam operated by the output and having a cam surface representing the ratio $V=\sqrt{2aD}$, and a cam follower on the link.

JAMES D. TEAR.
